Hot Chillys HC6131 Chil-Block Full Mask, [on-line]; [first made available to the Internet on Sep. 13, 2017 (see p. 2)]; [retrieved from the Internet on Aug. 14, 2018]; URL: see bottom of first page. (2 pgs). (Year: 2017).*

Primary Examiner — Karen S Acker*Assistant Examiner* — Jasmine Mlinarcik(74) *Attorney, Agent, or Firm* — Matthew J. Spark; Stefan J. Kirchanski; Zuber Lawler & Del Duca LLP(57) **CLAIM**

The ornamental design for a face mask, as shown and described.

DESCRIPTION

FIG. 1 is a perspective view of a face mask;
FIG. 2 is a top plan view of the face mask of FIG. 1;
FIG. 3 is a front view of the face mask of FIG. 1;
FIG. 4 is a rear view of the face mask of FIG. 1;
FIG. 5 is a side view of the face mask of FIG. 1; and,
FIG. 6 is another side view of the face mask of FIG. 1.
The broken lines illustrating a figure wearing the face mask
assists in illustrating how the claimed design may be worn
and depict environmental subject matter that forms no part
of the claimed design.
